Term of patent 7 years

(Cl. D14—27)

FIG. 1

FIG. 2

FIGURE 1 is a top perspective view of an auxiliary carrier for automobiles showing my new design; and

FIGURE 2 is a bottom perspective view thereof.

The characteristic feature of my design resides in the upstanding border having arcuate side elements curving downwardly in conjunction with depending, substantially V-shaped supports below said arcuate side elements as shown in the drawings.

I claim:

The ornamental design for an auxiliary carrier for automobiles, as shown and described.
